UNITED STATES PATENT OFFICE.

CHRISTIAN AALBORG, OF WILKINSBURG, PENNSYLVANIA, ASSIGNOR TO WESTING-HOUSE ELECTRIC AND MANUFACTURING COMPANY, A CORPORATION OF PENNSYLVANIA.

SWITCHING APPARATUS.

1,253,659.

Specification of Letters Patent. Patented Jan. 15, 1918.

Application filed December 26, 1913. Serial No. 808,745.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Switching Apparatus, of which the following is a specification.

My invention relates to switching apparatus, and it has special reference to so called "group switches" such as are commonly employed upon electric cars and locomotives.

One of the objects of my invention is to provide a group switch of the character referred to which shall embody a plurality of complete, self-contained and independent unit switches which are assembled in side-by-side relation.

Another object of my invention is to provide a group switch, of the type above indicated, which shall be simple and compact in arrangement, light and durable in construction and effective and reliable in operation.

A still further object of my invention is to provide a group switch, the several units of which may be constructed independently to form complete unitary devices which may be readily and cheaply assembled to form a switch group of any desired number of switches.

A still further object of my invention is to simplify and improve the arrangement of parts of a unit switch, whereby vertical space is economized.

Heretofore, group switches have embodied heavy and bulky supporting plates and frames upon which the various parts of the several switches were independently mounted. In such structures, the separate switches were in no sense "unit switches," inasmuch as they were not complete in themselves, but their component parts were separate and associated with the supporting brackets and frames independently. Moreover, it was necessary to make new patterns and castings for the supporting brackets and frames whenever the number and capacity of the several switches were varied.

In accordance with my invention, I provide a structure which, by reason of its peculiar arrangement of parts, obviates the difficulties hereinbefore mentioned, and provides a group switch of the true "unit switch" type having many advantages and

desirable features of construction which will 55 hereinafter be pointed out.

In the accompanying drawings, Figure 1 is a view, partially in section and partially in side elevation, of a device constructed in accordance with my invention. Fig. 2 is a 60 plan view, partially in section, of the apparatus shown in Fig. 1. Fig. 3 is a sectional view of a portion of a device embodying a modified form of my invention, and Fig. 4 is a detail view of an arcing terminal em- 65 ployed in my structure.

Referring to the drawings, the apparatus shown comprises a plurality of longitudinally disposed supporting rods 1 and 2 which may be carried by suitable brackets 70 3^a or other supporting means and upon which a plurality of unit switches 3 are mounted in side-by-side relation. The several unit switches 3 are complete in themselves and a switch group adapted for any 75 character of service or other requirements may be provided by assembling the desired number of unit switches together upon the supporting rods 1 and 2.

The unit switches 3 are of like construction, and each embodies a body member 5 comprising a supporting arm 6 and a portion 7 integrally associated therewith which constitutes a part of an electro-magnetically controlled fluid valve 8, relatively movable 80 8^a coöperating contact members 9 and 10, an operating mechanism 11 for the movable member, a fluid-actuated device 12 for effecting movements of said mechanism and movable contact member, and a blow-out device 90 13 which is associated with the coöperating contact members for the purpose of extinguishing the arc formed at the instant of circuit interruption.

The supporting arm 6 is substantially 95 horizontally disposed and is provided with a cupped or recessed portion 15 for a purpose to be hereinafter set forth and also with a clamping portion 16 which is adapted to coöperate with a clamping member 17 100 18 for the purpose of securing the body member 5 to the supporting rod 1.

The portion 7 of the body member 6 embodies an upwardly projecting member 19 which constitutes a stationary core of an 105 electro-magnet 20, and also an annular shell 21, between which and the core 19, a magnetizing coil 22 is placed. Centrally disposed

within the core 19 is a movable rod or core 23, the lower end of which projects into an opening or valve chamber 25 and is provided with two oppositely disposed valve plugs 26 and 27. The valve plugs 26 and 27 coöperate with other suitable parts, which will not be described, in view of their common use, for the purpose of admitting and releasing operating fluid to the operating device 12. 10 Communicating with the valve chamber 25, by means of a passage 28, is a supply chamber 29 through which the operating fluid is conducted.

It will be noted that the portion 7 of the 15 body member 5 projects downwardly below the supporting arm 6 and, secured to the inner surface 32 thereof, is a cylinder 33 which comprises a part of the operating device 12. Within the cylinder 33, which may 20 be a casting or constructed of spun sheet metal, or the like, is a movable piston 34, a piston rod 35 and a spring 36. The operating device 12 is disposed horizontally and the piston rod 35 is adapted for horizontal 25 movement.

A block 38 of insulating material is secured beneath the cylinder 33 and is provided with a plurality of resilient contact fingers 39 which are adapted for co-operative 30 engagement with movable contact members 40, the latter being carried by an arm 41 which is attached to the piston rod 35. The contact members 39 and 40 constitute the interlock switches for the switch group, and 35 control the energizing circuits of the several magnetizing coils 22, in accordance with well known practice.

The stationary switch member 9 is of L-shape and is secured to a block 45 of conducting material which is suitably attached 40 to the supporting arm 6 and is insulated therefrom by means of a plate or board 46 of insulating material. The conducting block 45 embodies an integral projecting 45 portion 47, which coöperates with a clip or clamp 48 to form a terminal for the purpose of making connection to conductors 49.

The movable contact member 10 is adapted 50 for substantially vertical movement and is disposed below the stationary contact member 9. Each of the coöperating contact members 9 and 10 is provided with an arcing terminal 50 of sheet material, which is bolted or otherwise secured thereto. The arcing 55 terminal 50 comprises a middle base portion 51 which is adapted to rest against a part of the main contact member and two substantially perpendicular side portions 52 which are inclined or curved slightly inwardly to meet at their outer ends, where they are riveted or otherwise united. The faces of the side portions 52 are disposed substantially at right angles to the working face 53 of the main contact member, and one 60 of the edges 54 thereof is in line with the

face 53 and forms a substantial continuation thereof. The side members 52 are of horn-shape and curve outwardly. The coöperating arcing terminals 50 have a substantially edge-to-edge engagement when the switch 70 members are closed and serve to interrupt the arc in a well-known manner during their separation.

The movable contact member 10 and its associated arcing terminal 50 are secured to an 75 end of a contact-carrying member 56 which is pivotally connected to an arm 57 of a bell crank lever 58 having another arm 59, the end of which has a pivotal connection to a member 60. The member 60 is associated 80 with the end of the piston rod 35 by means of an insulating coupling 61, which forms no material part of my present invention. A pin 63, that is associated with the contact-carrying member 56, projects through an 85 opening 64 in the bell crank lever 58 and thus serves to restrict the relative movement of the contact-carrying member 50 with respect thereto. The member 56 and its associated movable contact member 10 is 90 resiliently positioned by means of a spring 66 surrounding a rod 67, one end of which projects into an opening 68 in the member 56 and the other end of which has a sliding engagement with a projecting lug 69 on the 95 bell crank lever 58.

The bell crank lever 58, which serves as a connecting link between the vertically movable contact member 10 and the horizontally movable operating device 12, is pivoted, by 100 means of a pin 70, to a block 71 which is insulated by the insulating plate 46 from the supporting arm 6. The block 71 is engaged by a bolt 72 which projects through suitable openings in the plate 46 and the arm 6 and 105 is surrounded by an insulating collar 73 which is disposed in the cupped recess 15 already referred to.

The coöperating contact members 9 and 10 are partially inclosed by an arc chute 77 110 embodying upper and lower deflecting blocks 78 and 79 of insulating material and side plates 80 which are suitably attached to the sides of the insulating plate 46. The side plates 80 project below the lower deflecting 115 block 79, and a blow-out coil 83 is supported between them, directly beneath the contact members 9 and 10. The blow-out coil 83 has a central magnetizable core 84 and a pair of upwardly projecting magnetizable members or arms 85 which are located on the outside of the arc chute side members 80. Each of the arms 85 is provided, at its upper end, with a plate 86 of magnetizable 120 material, the plates being disposed substantially 125 opposite the contact members 9 and 10 for the purpose of concentrating the magnetic flux in the path of the arc when the switch is opened. A flexible shunt 87 connects the contact-carrying member 56 to one end (not 130

shown) of the blow-out coil 83, the other end 88 thereof being secured, by means of a bolt 89, to a conducting block 90. A clamping device 91 is also secured to the side of 5 the block 90 and constitutes the other terminal of the apparatus.

Attention is directed to the fact that each of the unit switches 3 is an entirety and independent of the adjacent units, all of the 10 parts being carried by the main body member 5. In assembling the several unit switches 3 in side-by-side relation, the supply chambers 29 register with one another in a suitable manner to form a continuous 15 supply passage or pipe. It is usually desirable to interpose gaskets or washers 92 of pliable material between adjacent units to insure tight connections. The rod 2 is preferably disposed centrally within the supply 20 passage 29 and serves as a tie-rod for clamping the several units together as well as a supporting member.

In the modification shown in Fig. 3, the portion 7 of the body member 5 is provided 25 with a valve chamber 25 and with a supply chamber 29 which communicates directly therewith. Furthermore, in place of employing a single tie and supporting rod 2, I use a plurality of such rods 2^a which project through suitable openings in the several 30 members 7 for the purpose intended.

Inasmuch as I have described the construction of my invention with particularity and the general operation of devices of this 35 type is well understood by those skilled in the art, no further description thereof will be given. Since the benefits and advantages of my invention may be secured by devices differing widely in structural details from 40 what I have shown and described. I desire that only such limitations shall be imposed as are indicated in the appended claims.

I claim as my invention:

1. A switching device comprising a supporting arm, an electro-magnetically actuated valve integral with said arm, co-operating contact members mounted upon said arm, a fluid-actuated device mounted upon said valve, and linkage means for oper- 45 atively connecting said fluid-actuated device to said contact members.

2. A switching device comprising a supporting arm, an electro-magnet secured to said arm, a valve adapted to be actuated by 50 said magnet and supported by said arm, co-operating contact members supported by

said arm, a fluid-actuated device secured to said valve, and means for operatively connecting said device to one of said contact members.

60

3. A switching device comprising a main supporting arm, a valve embodied in said arm, means supported by said arm for actuating said valve, a cylinder supported by said arm, a piston within said cylinder and switching means supported on said arm and adapted to be actuated by said piston.

4. In a unit switch, the combination with a single member embodying an electro-magnetically controlled fluid valve, a laterally 70 projecting integral supporting arm, and switching apparatus and an operating linkage therefor mounted upon said arm, of a fluid-actuated operating device disposed substantially at right angles to said electro-magnetically controlled fluid valve and adapted to actuate said operating mechanism.

5. In a unit switch, the combination with a single body member embodying an integral supporting arm and an electro-magnetically controlled fluid valve disposed substantially at right angles to each other, a fluid operated piston and containing cylinder associated with the valve portion of said body 85 and adapted to be governed by said valve, said cylinder and piston being disposed substantially parallel to said supporting arm, and a switching device and operating mechanism therefor secured to and suspended from 90 said arm and having an operative connection to said piston.

6. A unit switch embodying a main supporting arm, co-operating stationary and movable contact members suspended from 95 said arm, a magnet valve having a portion thereof integral with said arm, a fluid-actuated device controlled by said valve for operating said switch, and a blow-out coil suspended from said arm and having magnetizable pole pieces adjacent to the side of 100 said contact members, said valve, fluid-actuated device and blow-out coil being disposed in the same plane with the supporting arm.

In testimony whereof, I have hereunto subscribed my name this 18th day of Dec. 1913.

CHRISTIAN AALBORG.
